DOOR DEWARPING DEVICE

Fred G. Lando, Crystal Lake, Ill.

Application April 23, 1949, Serial No. 89,310

7 Claims. (Cl. 20—38)

1

This invention relates to a device for straightening warped doors. It is a common experience for wood doors, and especially new doors, to warp out of shape. The warping almost always takes place along the opening side which is opposite the side from which the door is hung. When in this condition a door cannot properly fit within its frame when closed, numerous leaks are present, and the general efficiency of the door is greatly impaired. To remedy this defect, it is necessary to remove the door so that it may be placed in a straightening press, or given other remedial treatment. In any event the door is rendered useless during the time it is being repaired and this causes great inconvenience and sometimes hardship.

My invention consists of a device which removes the warping in a door and restores it to its original intended shape, and at the same time allows full and unobstructed use of the door during the time it is undergoing the straightening process. The inconvenience and hardship normally encountered while repairing a warped door is thus eliminated. A further advantage is that the average unskilled layman can install and operate the device of my invention, thus eliminating unnecessary costs.

The objects of my invention are to provide a means for straightening a warped door without interfering with the continuous normal use of that door, and to provide a door straightener which is simple, effective, economical, and easy to use. Further objects and advantages will appear from the following description and reference to the drawing wherein—

Figure 1 is a perspective view showing my dewarping device attached to a door;

Fig. 2 is an enlarged sectional view, taken on line 2—2 of Fig. 1, showing the handle shaft and adjusting means;

Fig. 3 is a detail in section, taken on line 3—3 of Fig. 3; and

Fig. 4 which is a fragmentary view similar to Fig. 2 shows a modified construction.

As shown in Fig. 1, the device of my invention comprises an elongated presser bar B here shown as of channel cross section with inturned flanges 11 upon its open side. Contact blocks 12 of wood or other suitable material are slidably attached to the bar and protrude laterally from its open side. The contact blocks, here shown as two in number, are slotted at 14 along opposite sides to receive the flanges 11 whereby the blocks are confined slidably in place.

A spindle S extends through a selected hole

2

16 of which several are provided in the presser bar intermediately of its ends. This spindle, as shown in Fig. 2, is threaded at 17 for a portion of its length to accommodate a pair of nuts 18, and elsewhere is squared, as at 19, where it passes through a conventional latch mechanism 20 which is affixed to the door D which is to be dewarped. The squared ends of the spindle are entered into the sockets of door handles 22 and 23 to be secured thereto by screws 24 in the usual way. Anti-friction thrust bearings 25 may be positioned on the spindle, one adjacent the handle 22 and another adjacent the bar B, to offset binding resulting from advance of the nuts 18. In the 15 construction shown, the spindle S is elongated beyond the usual length, and on this account may be regarded as special.

In practice, the presser bar is placed in an upright position on the concave side of a warped door D with the contact blocks 12 facing the door to engage therewith at widely spaced points; the regular door handle spindle is removed so that the special elongated spindle S herein described may be substituted therefor, and the threaded 20 portion 17 of the spindle is fitted through one of the holes 16 in the bar. By tightening the nuts 18 pressure is exerted inwardly against the bar B and this pressure is transmitted to the door through the blocks 12 at points which may be 25 adjustably spaced apart. In this manner the warped door is pressed back to its original straight, flat shape and held rigidly in that position for as long as is necessary. The bearings 25 reduce friction to such an extent that the door 30 latch may be readily operated from the spindle when rotated in response to turning movement applied to the handle at either end thereof. The contact blocks may be slidably adjusted so as to exert pressure where it is most needed to accomplish 35 dewarping of the door. An additional means of adjustment is furnished by the plurality of spaced holes 16 at spaced points lengthwise of the presser bar, the spindle S being insertible through any one of them.

40 In Fig. 4 the spindle S' may be of the usual kind and standard length, and by replacing the knob at one end with the coupling sleeve 30 a second spindle 31 may be joined operatively thereto. The sleeve is interiorly squared lengthwise to receive the correspondingly shaped ends of the two spindles, and by means of screws 33 which extend transversely through the sleeve for threaded engagement with tapped holes in the spindles, these two parts are united for 45 concurrent rotative movement. A knob 34 is

mounted on the second spindle for operation thereof and of the first spindle and of the door latch connected therewith. As shown, the coupling sleeve is disposed both interiorly and exteriorly of the channeled presser bar B but free ⁵ of contact therewith so that when a pair of nuts ¹⁰ 35 on the second spindle 31 is advanced against the bar, this pressure will be transmitted through the door through blocks 36 which are adjustably carried by the bar as hereinbefore explained. This construction is advantageous in that it requires no special elongated spindle, but merely two spindles of the usual kind and length arranged end to end with an intercoupling means therebetween.

I claim:

1. A door dewarping device comprising an elongated presser bar having a transverse opening therethrough, spaced contact blocks carried by the bar for engagement with one face of a door at spaced points thereupon, an operating door latch spindle extending through the transverse opening of the bar and formed with screw threads adjacent the bar, means for holding the spindle against axial movement toward the bar, and a nut screw threaded upon the spindle, the nut being provided with means in pressure engagement with the bar arranged to transmit pressure therethrough to the contact blocks for application of such pressure to the door face at spaced localized points.

2. A door dewarping device according to claim 1 wherein the bar is of channel cross section and the contact blocks have portions entered into the bar channel and in sliding interlocking engagement therewith whereby to have capacity for adjustment in position lengthwise of the bar.

3. A door dewarping device according to claim 1 in which the bar is provided with a plurality of transverse openings spaced apart lengthwise thereof whereby the spindle may be extended through any selected opening to vary the position of the bar relative to the door.

4. A door dewarping device according to claim 1 in which the contact blocks are carried adjustably upon the bar each to occupy a selected position lengthwise thereof, and in which the

bar is provided with a plurality of transverse openings spaced apart lengthwise thereof whereby the spindle may be extended through any selected opening to vary the position of the bar relative to the door.

5. A door dewarping device comprising an elongated presser bar mounting spaced contact blocks for engagement with one face of the door, an operating spindle for the door latch, means disposed exteriorly of the door latch for holding the spindle in operative relation therewith, and means forming part of the exteriorly disposed means in thrust engagement with the bar arranged to advance the bar with pressure lengthwise of the spindle whereby to transmit pressure through the bar to the contact blocks for application to the door face at spaced localized points and without interference with oscillatory movements of the spindle for operation of the door latch.

6. A door dewarping device according to claim 5 in which the operating spindle consists of two like parts intercoupled end to end for unitary rotative movement, one part in connection with the door latch and the other part mounting the means in engagement with the presser bar.

7. A door dewarping device according to claim 5 in which the operating spindle consists of two parts arranged end to end, one part in connection with the door latch and the other part mounting the means in engagement with the presser bar, and a coupling sleeve interconnecting the two spindle parts in unitary relation and being disposed between the presser bar and the door.
